ATTORNEY

UNITED STATES PATENT OFFICE.

ARCHIBALD STILES, OF STEPHENSPOINT, KENTUCKY.

BROOM.

1,277,662.

Specification of Letters Patent. Patented Sept. 3, 1918.

Application filed February 4, 1918. Serial No. 215,275.

To all whom it may concern:

Be it known that I, ARCHIBALD STILES, a citizen of the United States, residing at Stephensport, in the county of Breckinridge 5 and State of Kentucky, have invented certain new and useful Improvements in Brooms, of which the following is a specification.

This invention relates to brooms, and its 10 object is to provide a superior broom at less cost than an ordinary broom by making the handle and broom brush detachable from each other, so that when the latter is worn out, it can be removed and a new one applied to the handle. The handle can therefore be used over and over again, thus saving the cost of a number of handles in the final cost of the brooms. The invention also 15 has for its object to provide a simple assemblage of parts, whereby an additional 20 saving is effected.

In the present construction of brooms, much of the valuable part of the broom corn is wasted as it must reach up far enough on 25 the handle to be securely fastened thereto, and when the broom is worn out, this valuable part is lost with the handle. The wiring of the broom corn to the handle is the most difficult part in the process of broom 30 making, and the present invention therefore contemplates a novel and improved means for assembling the broom corn so that the broom can be easily and cheaply constructed, making it possible to market the broom 35 at a reduced cost.

Other objects and advantages of the invention will be pointed out in the detailed description appearing hereinafter, and although the preferred embodiment of the invention 40 has been shown, it is to be understood that various changes and modifications in the structural details disclosed may be made without a departure from the spirit and scope of the invention as claimed hereinafter.

In order that the invention may be better understood, reference is had to the accompanying drawing forming a part of this specification, in which drawing, Figure 1 45 is an elevation of the broom; Fig. 2 is an enlarged vertical section on the line 2—2 of Fig. 1; Fig. 3 is an elevation showing certain parts of the broom removed and a bridle plate swung open, and Figs. 4 and 5 50 are sections on the lines 4—4 and 5—5, respectively, of Fig. 2.

Referring specifically to the drawing, 10 denotes an ordinary broom brush constructed of broom corn or other suitable strands, and provided with encircling wires 11 for 60 tying the strands together. An ordinary wooden handle is shown at 12.

To the forward end of the handle 12 is fastened by screws or other suitable means 13, a cover 14 of sheet metal into which this 65 end of the handle extends for a short distance. This cover is open at the bottom, and it is of crowned contour to give a finished appearance to the broom.

To the end of the handle which is located 70 in the cover 14 is secured by a screw or other suitable means 15, a cross head 16, which may be a wooden block. The butt end of the brush 10 seats against the cross head 16, the latter being shaped and dimensioned to 75 fit the brush end.

On top of the cross head 16 is secured by screws or other suitable fasteners 17, a sheet metal plate 18 having upturned ears 19 at its ends, said ears being located at the ends 80 of the cross head.

Beneath the cover 14 is located a bridle consisting of plates 20 and 21, respectively, which are curved in cross section to fit around the upper portion of the brush 10 85 and house the same. The plate 21 is hinged to the ears 19 at the ends of the cross head 16, said plate having projecting tongues 22 extending to the ears and connected thereto by pivot pins 23 which pass through the 90 cover 14 as shown in Fig. 2. By providing a pivotal connection between the plate 21 and the cross head 16, said plate can be swung outward of the brush 10 for a purpose to be presently described. 95

On opposite sides of the handle 12 are fastened by the screws 13 or other suitable means, resilient strips 26 of sufficient length to locate laterally extending branches 27 at their outer ends alongside the brush 10, said 100 branches having inwardly directed barbs 28 adapted to pierce the brush. The strips are drawn together to force the barbs 28 into the brush 10, by a screw 29 carried by one of the strips 26 and threaded into a lug 30 105 on the other strip. The strips 26 are housed in the cover 14 and the bridle plates 20 and 21.

Around the bridle plates 20 and 21, adjacent to their outer ends, is placed a tension 110 member in the form of a sheet metal band which is in two sections indicated at 31 and

32, respectively, the former fitting outside the bridle plate 20, and latter outside the bridle plate 21. The two sections are pivotally connected as shown at 33, and the section 32 is split, with its ends overlapping, and said overlapping ends formed with registering slots 34 to receive a screw 35 passing into the brush where the strands are packed together tight enough to hold the screw. Upon tightening up the band sections 31 and 32, the bridle plates 20 and 21 are tightly clamped around the brush, giving proper support to the same when in use.

It will be noted that the edges of the bridle plates 20 and 21 do not meet, and hence two cover strips 36 are provided, the same being secured to the handle 12, and extending over the outside of the cover 14, and along the space between the edges of the bridle plates, their lower ends seating under the clamping band sections 31 and 32.

By the structure hereinbefore described, the brush 10 can be readily renewed when worn. To remove the brush, the band sec-

tions 31 and 32 are removed, and the bridle 25 plate 21 is swung open as shown in Fig. 3, which leaves the adjacent strip 26 accessible to remove its barbs 28 from the brush, after which the latter can be lifted out. By a reversal of this operation, the new brush is 30 easily and quickly applied.

I claim:

The combination with a broom brush and its handle; of a cross head on the handle end against which the inner end of the brush 35 abuts, locking strips for the brush carried by the handle and having barbs which pierce opposite sides of the brush, bridle plates fitting over the locking strips and inclosing the inner portion of the brush, one of said 40 plates having a pivotal connection with the cross head, means for clamping the bridle plates around the brush, and cover strips carried by the handle and extending over the adjacent edges of the bridle plates. 45

In testimony whereof I affix my signature.

ARCHIBALD STILES.
